UNITED STATES PATENT OFFICE.

JOHN J. O'LEARY, OF HEALDSBURG, CALIFORNIA.

GAS-ENGINE STARTER.

1,017,453.

Specification of Letters Patent. Patented Feb. 13, 1912.

Application filed February 25, 1911. Serial No. 610,839.

To all whom it may concern:

Be it known that I, JOHN J. O'LEARY, citizen of the United States, residing at Healdsburg, in the county of Sonoma and State of California, have invented new and useful Improvements in Gas-Engine Starters, of which the following is a specification.

This invention relates to starting devices and particularly to a means for starting the 10 engine shaft of self-propelled vehicles.

It is the object of the present invention to provide a power conserving apparatus which may be mechanically energized by the driven shaft of the engine when the latter is running; which will automatically uncouple itself from a controlling device when the power conserving elements have been sufficiently wound or energized; which is simple, reliable and effective in operation; and 20 which may be readily mounted or dismounted in position upon the shaft.

The invention consists of the parts and the construction and combination of parts, as hereinafter more fully described and 25 claimed, having reference to the accompanying drawings, in which—

Figure 1 is a vertical longitudinal section through the starting device, with some of the parts in elevation. Fig. 2 is a plan view partly broken away, of the device, showing the releasing pawls. Fig. 3 is a side view partly broken away to show the roller clutch. Fig. 4 is a perspective detail of the dogging hook. Fig. 5 is a detail 35 cross section at the stop latch. Fig. 6 is a detail of the ring to which the drive spring is attached.

In the present embodiment of my invention 2 represents a shaft adapted to be 40 driven by any suitable source of power, as a gas engine, not shown, but such, for instance, as is commonly employed in the propulsion of vehicles.

In self-propelled vehicles employing internal combustion engines the common procedure in starting up the engine is to manually crank it by means usually provided for that purpose, and in this invention there is connected to the shaft 2 an automatic 45 starting device, indicated as at 3, and which comprises a shiftable collar 4 mounted upon the shaft 2 and having radial teeth 5 formed upon one of its faces. These teeth 5 are adapted to engage with complementary teeth 6 formed upon an adjacent end of a 50 fixed clutch member 7 on the shaft 2.

The collar 4 is of somewhat larger diameter than the fixed clutch member 7 and is normally thrust into engagement with the teeth 6 by an expansion spring 8 reactive 60 upon a disk 9, forming one side of the housing of the starting device 3.

The shiftable clutch collar 4 may be provided with a flange, as at 10, which may be pressed outwardly by the spring 8 against a 65 wall 11 of the starting device. Secured to the periphery of the clutch collar 4 is a spring or appropriate device 12, the outer end of which is connected to a ring 13 having a chamber 14, which is semi-circular in 70 cross-sectional area, and which is mounted with a limited amount of play upon a transverse pin 15 preferably made triangular in cross-section at the portion embraced by the member 13. The pin 15 is provided at suitable 75 portions with cylindrical surfaces 16 supported in suitable bearings 17 in the casing and there is also fixed upon the pin 15 a latch or bolt member 18 adapted to be projected circumferentially through the cylindrical drum 19, which is attached to the disk 9 of the casing.

If desired, a removable plate 20 may be secured to the drum 19 for the protection of the mechanism. 85

When the spring 12 is unwound, or in other words, released from tension, it allows the connection 14 to move the pin 15 in its bearings and rock the latching member 18 so that its outer end will project through the 90 drum 19 and come into engagement with a movable detent 21, which is here shown as being connected to one end of a rod 22, by which a brake band 23 may be closed about the periphery of the drum 19 by the operator of the vehicle. 95

In operation and in a normal condition the shiftable clutch collar 4 is thrust outwardly by its co-operative spring 8 until the teeth 5 and 6 intermesh, and if the engine 100 shaft 2 is being driven, power will be transmitted through the fixed member 7 to turn collar 4 and thus wind the spring 12 with sufficient force to carry the drum 19 and its associated pins around simultaneously with, and in the direction of rotation of, the shaft 2 until the locking bolt 18 encounters the external abutment 21. When the bolt 18 has engaged the abutment member 21, the rotation of the drum 19 is interrupted and the 110 continued rotation of the shaft 2 with its member 7 further winds the spring 12, in-

creasing the tension, the degree of which will be determined by practice, and sufficient to start the shaft 2 from an idle position at the desire of the operator. When the spring 12 has been wound to a predetermined tension, it will draw down the upper end of the spring and its connection 14, thus rocking the pin 15 and pulling the bolt 18 out of engagement with the restraining abutment 21. 10 Having thus placed the spring 12 under tension and its release having been automatic by the withdrawal of the locking bolt 18 through the periphery of the drum 19, the tension of the spring 12 will be exerted to 15 pull the drum 19 circumferentially about the shaft 2; and in order to prevent this premature unwinding of the spring 12 after it has been wound by its shaft 2, there is formed upon one side of the casing disk 9 20 a cylindrical flange 24 having a smooth concentric interior wall 25. Upon the shaft 2 is keyed a fixed hub 26, upon the exterior periphery of which is mounted a plurality of friction devices, here shown as rollers 27 25 adapted to ride upon the eccentric cam surfaces 28 of the hub 26. Spaces 29 are thus formed around the periphery of the hub 26, which will allow the rollers 27 to be disengaged from the surfaces of the adjacent 30 members 26-24, but the eccentric surfaces 28 of the hub 26 are such that when the drum 19 tends to move in the same direction about the hub 26 as the rotation of the shaft 2, the anti-friction members 27 will become effective to cause the two elements to interlock and thereafter to travel uniformly together. 35

After the starting device has been installed in position on the shaft 2, the latter is given its initial rotation by any suitable 40 means, as by cranking or otherwise, to first start the engine, and after this has been accomplished the spring 12 of the starting device can be automatically wound during the rotation of the engine shaft 2, as has been 45 hereinbefore stated.

When the operator wishes to automatically start the rotation of the shaft 2 from the idle position, he shifts the collar 4 inwardly by means of an appropriate lever 30 50 fulcrumed at 31 upon suitable bearings in the vehicle. The lower end of the lever 30 is forked and provided with oppositely disposed abutment faces 32, which will swing in and encounter the teeth 5 of the collar 4 55 and thus prevent its reverse revolution about the shaft 2, as it is disengaged from the restraining teeth 6 of the fixed member 7. When the lever 30 is rocked sufficiently to 60 carry the teeth 5 of the shiftable collar 4 clear of the member 7, the force of the spring 12 exerted upon the pin 15 will pull the casing or drum 19 in the direction of the normal rotation of the shaft 2, causing the friction rollers 27 to automatically embrace the hub 65 portion 26 and thus mechanically and auto-

matically rotate the shaft 2; the shiftable collar 4 meanwhile being held stationary by the hook portion 32 of the lever 30.

As before stated, the spring 12 is designed to be wound to a sufficient tension to give the 70 shaft 2 a sufficient number of rotations, as two, three or more, to start the engine. The lever 30 is normally withdrawn from engagement with the collar 4 by means of the spring or other suitable device 33. 75

The band brake 23 is provided as an auxiliary means for preventing the rotation of the shaft 19 in the event that the locking elements should become temporarily inoperative; the brake 23 enabling the operator to 80 manually control the rotation of the drum 19 when the spring 12 is being mechanically wound by connection to the shaft 2.

An important feature of the present invention is the provision of means whereby 85 the device can be readily and easily connected and disconnected to a shaft, and to accomplish this I have shown these means in the present instance as comprising a short section of shaft 34 which is threaded at 35 90 on each end and also transversely slotted, as at 36. The adjacent end of the engine shaft 2 is provided with an interlocking portion 36 adapted to be inserted into a slotted part of the sectional shaft 34 and the two contiguous or abutting ends of shafts 2 and 36 95 safely locked by means of internally threaded sleeves 37 adapted to be threaded on the portions 35.

Having thus described my invention, what 100 I claim and desire to secure by Letters Patent is—

1. The combination of a driven shaft, a clutch hub keyed upon said shaft, a flanged disk adapted to drive said hub in one direction, friction rollers interposed between the periphery of said hub and the inner surface of the flange of the disk, a casing removably attached to the flanged side of the disk, a housing secured to the other side of said 110 disk, a spring inclosed in said housing, a pin supported adjacent the periphery of the housing and to which one end of said spring is connected, a collar having radial teeth upon one of its faces slidably mounted upon 115 said shaft and projecting inwardly into the aforesaid housing and having attached the other end of the spring, a complementary clutch member secured upon the shaft, having teeth adapted to engage with the teeth 120 of said collar, a lever adapted to engage and restrain the collar, and a spring bearing against one side of the flanged disk and normally effective to thrust the toothed collar 125 into engagement with the clutch member, and means for restraining the housing during the winding of the main spring.

2. The combination of a driven shaft, a clutch hub keyed upon said shaft, a flanged disk adapted to drive said hub in one 130 direction,

tion, friction rollers interposed between the periphery of said hub and the inner surface of the flange of the disk, a casing removably attached to the flanged side of the disk, a housing secured to the other side of said disk, a spring inclosed in said housing, a pin supported adjacent the periphery of the housing and to which one end of said spring is connected, a collar having radial teeth upon one of its faces slidably mounted upon said shaft and projecting inwardly into the aforesaid housing and having attached the other end of the spring, a restraining lever engageable with the collar, a complementary clutch member secured upon the shaft, having teeth adapted to engage with the teeth of said collar, a spring bearing against one side of the flanged disk and normally effective to thrust the toothed collar into engagement with the clutch member, means for restraining the housing while the main spring is being wound, and means for disengaging the slideable clutch collar.

3. The combination of a driven shaft, a clutch hub keyed upon said shaft, a flanged disk adapted to drive said hub in one direction, friction rollers interposed between the periphery of said hub and the inner surface of the flange of the disk, a casing removably attached to the flanged side of the disk, a housing secured to the other side of said disk, a brake operative upon said housing, a spring inclosed in said housing, a pin supported adjacent the periphery of the housing and to which one end of said spring is connected, a collar having radial teeth upon one of its faces slidably mounted upon said shaft and projecting inwardly into the aforesaid housing and having attached the other end of the spring, a complementary clutch member secured upon the shaft, having teeth adapted to engage with the teeth of said collar, a spring bearing against one side of the flanged disk and normally effective to thrust the toothed collar into engagement with the clutch member, and means for disengaging the slideable clutch collar, said means including a lever having projections adapted to engage the teeth of said collar to prevent its rotation when disengaged from its complementary clutch.

4. A device comprising a driven shaft and a power conserving instrumentality comprising a toothed shiftable collar slidable upon said shaft, a restraining lever engageable with said collar, a flexible member secured to said collar, a housing for said member to which it is also connected, means for imparting power to said instrumentality, said means including a toothed member fixed upon said driving shaft coöperative with the shiftable collar, a brake operative upon the housing, and an automatic releasing device connected to said flexible

member, said device comprising a rockable pin secured to one end of the flexible member and carrying a tiltable pawl engageable with an abutment and releasable therefrom when said member is sufficiently tensioned. 70

5. A device comprising a driven shaft and a power conserving instrumentality comprising a toothed shiftable collar loose upon said shaft, a flexible member secured to said collar, and a housing for said member to which it is also connected, means for imparting power to said instrumentality, said means including a toothed member fixed upon said driving shaft coöperative with 80 the shiftable collar, means whereby the stored energy of the flexible member may be transmitted to initially turn the shaft from a position of rest and an automatic releasing device connected to said flexible member, said device comprising a rockable pin secured to one end of the flexible member and carrying a tiltable pawl engageable with an abutment and releasable therefrom when said member is sufficiently tensioned. 90

6. A device comprising a driven shaft and a power conserving instrumentality comprising a toothed shiftable collar loose upon said shaft, a restraining lever engageable with said collar, a flexible member secured to said collar, and a housing for said member to which it is also connected, means for imparting power to said instrumentality, said means including a toothed member fixed upon said driving shaft coöperative 95 with the shiftable collar, and means whereby the stored energy of the flexible member may be transmitted to initially turn the shaft from a position of rest, said means including a clutch comprising a flange formed on a part of the housing, a clutch hub secured upon said shaft, friction devices interposed between the inner surface of said flange and the periphery of said hub, said friction devices being normally 100 ineffective when the shaft is turned independently of the housing and a brake operative to restrain the housing. 110

7. A device comprising a driven shaft and a power conserving instrumentality 115 comprising a toothed shiftable collar loose upon said shaft, a restraining lever engageable with said collar, a flexible member secured to said collar, and a housing for said member to which it is also connected, means 120 for imparting power to said instrumentality, said means including a toothed member fixed upon said driving shaft coöperative with the shiftable collar, means whereby the stored energy of the flexible member 125 may be transmitted to initially turn the shaft from a position of rest, said means including a clutch comprising a flange formed on a part of the housing, a clutch hub secured upon said shaft, and friction devices 130

interposed between the inner surface of said flange and the periphery of said hub, said friction devices being normally ineffective when the shaft is turned independently of the housing, a spring interposed between a part of the housing and the shiftable collar normally effective to shift the latter into engagement with the fixed clutch member and a brake operative to restrain the housing.

8. A device comprising a driven shaft and a power conserving instrumentality comprising a toothed shiftable collar loose upon said shaft, a flexible member secured to said collar, and a housing for said member to which it is also connected, means for imparting power to said instrumentality, said means including a toothed member fixed upon said driving shaft coöperative with the shiftable collar, means whereby the stored energy of the flexible member may be transmitted to initially turn the shaft from a position of rest, said means including a clutch comprising a flange formed on a part of the housing, a clutch hub secured

upon said shaft, and friction devices interposed between the inner surface of said flange and the periphery of said hub, said friction devices being normally ineffective when the shaft is turned independently of the housing, a spring interposed between a part of the housing and the shiftable collar normally effective to shift the latter into engagement with the fixed clutch member, said fixed clutch member being adapted to 35 rotate the shiftable collar when the shaft is power driven to place the flexible member under tension, means for preventing the housing from rotating in the direction of rotation of the shaft when the winding 40 members are intermeshed and a lever engageable with the collar.

In testimony whereof I have hereunto set my hand in the presence of two subscribing witnesses:

JOHN J. O'LEARY.
